UNITED STATES PATENT OFFICE.

WILLIAM RUFF, OF NEW YORK, N. Y.

HYDROCARBON-VAPOR GENERATOR.

Application filed July 25, 1918. Serial No. 213,337.

To all whom it may concern:

Be it known that I, WILLIAM RUFF, a citizen of the United States, residing at the borough of Manhattan, in the city, county, 5 and State of New York, have invented certain new and useful Improvements in Hydrocarbon-Vapor Generators, of which the following is a specification, reference being had therein to the accompanying 10 drawings, which form a part thereof.

My invention relates to hydrocarbon vapor generators, and more particularly to a type thereof wherein the hydrocarbon is delivered under pressure to a vaporizer tube, and the heat for vaporizing the fluid is derived from the flame of the gases produced 15 by the generator.

A generator made in accordance with my invention is particularly adapted for use in 20 connection with illuminating lamps, and is designed primarily to permit the use in such lamps of kerosene oil, without likelihood of the formation of carbon within the vaporizer tube, or the stoppage of the discharge opening of said tube by small particles of carbon.

In vaporizing kerosene without the production of carbon within the vaporizer tube, I have found it essential to provide for the 25 rapid transmission of heat to the oil within the tube so as to secure the desired uniform high temperature; to use a tube which in addition to its capacity for high conductivity of heat, will have a surface to which carbon will not readily adhere, thus preventing the accumulation of carbon particles of sufficient size to choke the discharge opening; and to rapidly vaporize the hydrocarbon and discharge it from the vaporizer tube under conditions which will produce a 30 superheated vapor adjacent the discharge opening.

Generators of the type to which my invention relates are provided with a starting pan surrounding the vaporizer tube, and 35 usually the pipe through which the oil is delivered to said tube has in its length a control valve so that the oil may be excluded from the tube until it has attained the proper vaporizing temperature.

50 In a generator made in accordance with my invention, I have found such a valve not only to be unnecessary, but in a measure to be dangerous owing to likelihood of the

bursting of the tube with the development of excessive pressures therein upon the cutting off of the supply of hydrocarbon when shutting down the generator. 55

I have also found it desirable to so arrange the inlet of the mixing tube that air will be drawn thereinto by the vapor jet 60 from a source of air somewhat remote from the flame, the air inlet tube, however, being subjected to heat so as to preheat the air entering into the inflammable mixture.

The elimination of the control valve in 65 the oil supply pipe, necessitates the control of the flame through the regulation of the pressure in the supply tank, pressure being developed after the initial heating of the vaporizer and the flame being extinguished 70 by the relief of this pressure, so as to permit the pressure within the vaporizer tube to be relieved through the supply tank, and thus avoid likelihood of the development of 75 excessive pressures within said tube with a resultant likelihood of the bursting of the tube.

The invention consists in the novel features of construction and combination of parts hereinafter set forth and described, 80 and more particularly pointed out in the claims hereto appended.

Referring to the drawings,

Fig. 1 is a view partly in elevation and partly in section of a generator embodying 85 my invention, as applied to an illuminating lamp;

Fig. 2 is a detail view of a portion of the vaporizer tube, partly in section; and

Fig. 3 is a detail view in section of the 90 filling valve and pressure controlling valve for the supply tank.

Like letters refer to like parts throughout the several views.

In the embodiment of my invention 95 shown in the drawings, *a* indicates a supply tank having a pedestal *b* which may be hollow or solid, as desired. Surmounting the pedestal is a fitting *c* supporting a starting pan *c'* which is of the usual construction, embodying a metal cup filled with asbestos or other non-inflammable and absorbent material, adapted to receive a charge of alcohol. Carried by the pan *c'* is a vaporizer tube *d* the detailed construction of 100 which will be more fully described herein-

after. The lower end of the vaporizer tube *d* is in communication with the supply tank *a* through the pipe *e* which terminates adjacent the bottom of said tank, and connects with a suitable passageway formed in the fitting *c*, the other end of which passageway is in communication with the vaporizer tube *d*.

In this manner, when the contents of the tank *a* are placed under air pressure, the kerosene or other hydrocarbon in the tank will be forced upwardly through the tube *e* into the vaporizer tube *d*.

Supported from the pedestal *b* by the bracket *f* is a head fitting *g* having gas supply conduits *g*' and *g*'', each of which is adapted to supply the inflammable mixture to mantles as *g*''' arranged upon opposite sides of, and adjacent the vaporizer tube *d*. This fitting includes therein the mixing tube *h* which communicates with atmosphere through the air supply pipe *h*' by means of which the entire head fitting is supported from the bracket *f*. This air supply pipe *h*' opens downwardly through the fitting *f* so as to draw its air from a point below and remote from the mantles *g*''', (two of which are ordinarily used) but extends adjacent these mantles so that the air passing therethrough will be heated before being mixed with the vapor discharged from the tube *d*.

The end of the tube *d* projects into the mixing tube *h* for the required distance and has a fairly close fit with the opening in said tube through which it passes, this opening being relied upon merely to permit the insertion of said vaporizer tube within said mixing tube, and not serving in any way as a source of air supply for the mixture.

Carried by the tank *a* is a removable plug *i* which has the three-fold function of permitting the filling of the tank *a*, of permitting the development of the required air pressure within said tank, and of controlling the flame through the regulation of this pressure. The plug *i* is provided with an ordinary ball check valve *j* which serves to hold pressure in the tank as it is being developed and thus permit the convenient use of a pump, which itself has no check valve therein. Communicating with the casing of the check valve *j* is an opening *i*', the lower part of which is conical as shown, to form a valve seat *i*'', and the upper part of which is screw-threaded to receive the screw plug *k*, the lower end *k*' of which is conical to conform to the conical valve seat *i*''. The check valve casing has a reduced opening *i*''' extending therefrom into the opening *i*', the plug *k* being provided with a projecting pin *m* adapted, when the plug is being tightened, to project through said opening *i*''' and unseat the ball of the check valve *j* before the said plug seats upon the valve seat *i*''.

This construction permits the venting of the tank

a in a manner to relieve the pressure upon the contained oil when it is desired to extinguish the flame.

Extending into the plug *k* is a channel *k*'' having an outlet *k*''' opening outwardly of said plug at some point of the conical part *k*' thereof. An ordinary pressure gauge *i*'' is connected with the opening *i*''' and carried by the plug *i*.

I have found in actual practice, in order to satisfactorily vaporize kerosene oil, that the vaporizer tube *d* must have very thin walls in order to conduct heat to the kerosene within same, with sufficient rapidity to properly and rapidly vaporize it. I have also found that it is essential to make this tube of a material which will not readily carbonize, or which has little or no affinity for carbon.

The most satisfactory metal I have found for this tube is aluminum, but I have also found that aluminum of sufficiently thin gauge, does not possess enough strength to resist the bursting strains developed within the tube. To meet this condition I provide a composite mixing tube, the outer shell *d*' of which is formed of a metal possessing great tensile strength, and one upon which soot will not accumulate, such as nickel steel. This outer shell, I line with an aluminum shell *d*'', which, as above stated, has little or no affinity for carbon. Both shells are closed at one end as *d*'''. To prevent the accumulation of carbon at the discharge orifice, I insert a plug *d*''' in the end *d*'' of both shells *d*' and *d*'', which plug is of aluminum and has extending therethrough a hole of uniform diameter throughout, which may be as small as five one-thousandth of an inch, although when a greater volume of gas is required, this dimension may be increased. In this manner the oil and oil vapor passing through the vaporizer tube *d* contacts solely with aluminum and the composite wall may be made sufficiently thin to ensure the desired rapid conductivity of heat to the oil and vapor within the tube.

The operation of the herein described generator is substantially as follows:-

When starting the generator, the plug *i* is removed and a quantity of kerosene charged into the tank *a*. The plug *i* is then replaced. A small quantity of alcohol is then placed in the pan *c*' and ignited, the flame therefrom impinging upon the exterior of the tube *d* raising the metal thereof to the desired high temperature. During this time no kerosene is delivered to the tube *d*.

When said tube has been properly heated, the screw plug *k* is actuated to unseat the conical end thereof from the valve seat *i*'', thus forming a clearance between said plug and said seat.

Air is then pumped through the plug *k*

and the plug i into the tank a , the check valve j holding this pressure during each intake stroke of the pump.

The gauge i^3 will indicate the pressure 5 developed within the tank a .

As the pressure within the tank a is raised, oil will be fed therefrom through the tube e to the vaporizer tube d , the contact 10 of this oil with the heated walls of said vaporizer tube reducing the oil to a vapor and developing a counterpressure in said tube which will substantially equal the pressure in the tank a .

With the development of this vapor in 15 the tube d , it will escape therefrom through the nozzle opening, in jet form and flow through the supply pipes g' and g^2 to the mantles g^3 where it will be ignited by the flame from the starting pan c' .

20 As the vapor is discharged into the mixing tube h it will draw in an adequate supply of air to secure the proper mixture.

By using a minute discharge opening in 25 the tube d it is possible to secure a choke effect resulting in the development of high vapor pressure within the tube, thus ensuring at all times a substantial volume of vapor adjacent said nozzle and within the direct range of the heat radiated from the 30 mantles g^3 . In this manner the vapor will be superheated.

With the continued burning of the lamp, 35 the air which is drawn through the supply pipe h' will be heated by the radiant heat from the mantles g^3 , thus ensuring a more intimate mixture of the vapor and air and securing a more stable inflammable mixture.

When the desired pressure has been developed in the tank a , the plug k is tightened 40 and, thus seating the conical end thereof on the valve seat i^2 and avoiding a loss of pressure through leakage at this point, it having been found that the check valve j does not form a sufficiently tight joint to 45 hold the pressure. As the plug k is tightened, the pin m thereof will pass through the reduced opening i^4 and open the check valve j which, with the seating of the conical end of the plug k , no longer has any 50 function.

When the conditions above referred to are established, the lamp will continue to burn with undiminished brilliancy for a 55 number of hours before the pressure in the tank a will be reduced to a point where there will be any substantial variation in the quality or quantity of the mixture.

If, however, the mantles g^3 should lose some of their brilliancy, the plug k may be 60 unloosened, the check valve j acting instantly to prevent the escape of air when the pin m recedes beyond the seat for the ball of said valve, and additional air may be pumped into the tank a to raise the pressure. 65

The gauge i^3 is used merely to determine the pressure within the tank a and to permit the development of a known pressure condition within said tank.

When it is desired to extinguish the 70 lights, it is merely necessary to actuate the plug k until the pin m carried thereby, prevents the ball of the check valve j being seated, whereupon the air within the tank a will escape, reducing the pressure in the 75 tank and stopping the feed of oil to the tube d . Oil already in the tubes d and e will return to the tank a and the vapor pressure in the former will be relieved through 80 said tank so as to avoid all likelihood of the development of pressure sufficient to burst said tube.

It will be observed that after entering the vaporizer tube d , the kerosene and its 85 heated vapors will contact only with the aluminum shell d^2 and the aluminum plug d^4 , upon which carbon will not accumulate. By this composite tube construction, I am 90 enabled to not only prevent fouling of the interior of the tube d and of the discharge opening thereof with carbon, but secure sufficient strength in the tube to resist bursting stresses.

I have found nickel steel to be highly satisfactory for the outer shell, since no carbon 95 deposit forms thereon. The absence of carbon from the interior and exterior of the tube ensures a continued, uniform application of heat throughout the portion of the tube adjacent the flame, thus contributing 100 towards uniformity in the density, saturation and pressure of the vapors while within in the tube.

It is not my intention to limit the invention 105 to the detailed use of the invention herein described, it being apparent that the vapors generated may be used for heating as well as illuminating purposes.

Having described the invention, what I 110 claim as new and desire to have protected by Letters Patent is:—

1. A hydrocarbon vapor generator embodying therein in combination, an oil supply tank, a burner, a vaporizer tube having a thin wall and a discharge opening therefrom, composed of an outer shell of a metal having high tensile strength, and an inner shell of aluminum, both of said shells having closed ends and an aluminum plug mounted in said closed end, said plug having a minute discharge opening therethrough communicating with the interior of the tube, said tube being so positioned as to be subjected to the radiant heat from the burner, means whereby an air cushion may be developed in said tank, and a pipe connection between said tank and said tube, whereby oil under pressure will be delivered to said tube. 115 120 125

2. A hydrocarbon vapor generator em- 130

bodying therein in combination, an oil supply tank, a burner, a vaporizer tube having a thin wall and a discharge opening therefrom, composed of an outer shell of a metal having high tensile strength, and an inner shell of aluminum, both of said shells having closed ends and an aluminum plug mounted in said closed end, said plug having a minute discharge opening there-through communicating with the interior of the tube, said tube being so positioned as to be subjected to the radiant heat from the burner, means whereby an air cushion may be developed in said tank, a pipe connection between said tank and said tube, whereby oil under pressure will be delivered to said tube, said pipe connection having no valve in the length thereof, and means whereby the pressure in said tank may be relieved to extinguish the flame.

3. A hydrocarbon vapor generator embodying therein in combination, an oil supply tank, a burner, a vaporizer tube having a thin wall and a discharge opening therefrom, composed of an outer shell of a metal having high tensile strength, and an inner shell of aluminum, both of said shells having closed ends and an aluminum plug mounted in said closed end, said plug having a minute discharge opening there-through communicating with the interior of the tube, said tube being so positioned as to be subjected to the radiant heat from the burner, means whereby an air cushion may be developed in said tank, a pipe connection between said tank and said tube, whereby oil under pressure will be delivered to said tube, said pipe connection having no valve in the length thereof, and means whereby the pressure in said tank may be relieved to extinguish the flame, comprising a removable filling plug having a valve seat and a check valve therein, a valve plug having an air passage therethrough, and means carried by said valve plug adapted to control said check valve whereby air may be delivered to said tank or the pressure therein may be relieved through said valve plug.

4. A hydrocarbon vapor generator embodying therein in combination, an oil supply tank, a burner, a vertically extending vaporizer tube having a thin wall and a discharge opening therefrom, said tube being so positioned as to be subjected to the

radiant heat from the burner and being free from interior obstructions, a head fitting having a mixing tube into which said vaporizer tube discharges, a supply pipe leading therefrom to said burner, an air supply pipe supporting said head fitting, one end of which opens into said mixing tube, and the other end of which opens at a point remote from said burner, said pipe being subjected to radiant energy from said burner, whereby the air entering the mixture is pre-heated, means whereby an air cushion for causing and controlling the flow of liquid to said tube may be developed in said tank, and a pipe connection between said tank and said tube, whereby oil under pressure will be delivered to said tube, said pipe being of substantially uniform nonvariable capacity throughout the entire length thereof, whereby the feed of oil from said tank to said tube will be governed solely through the relative pressures in said tank and said tube.

5. A hydrocarbon vapor generator embodying therein in combination, an oil supply tank, a burner, a vaporizer tube having a minute discharge opening therethrough communicating with the interior thereof and being so positioned as to be subjected to the radiant heat from the burner, means whereby an air cushion for causing and controlling the flow of liquid to said tube may be developed in said tank, a pipe connection between said tank and said tube, whereby oil under pressure will be delivered to said tube, said pipe connection having no valve in the length thereof, and means whereby the pressure in said tank may be relieved to extinguish the flame, comprising a removable filling plug having a valve seat and a check valve therein, a valve plug having an air passage therethrough, and means carried by said valve plug adapted to control said check valve whereby air may be delivered to said tank or the pressure therein may be relieved through said valve plug.

In witness whereof I have hereunto affixed my signature, in the presence of two subscribing witnesses, this 18th day of July, 1919.

WILLIAM RUFF.
